UNITED STATES PATENT OFFICE.

JAMES C. BEARDSLEE AND WILLIAM J. CRITCHLEY, OF CLEVELAND, OHIO, ASSIGNORS TO THE SHERWIN - WILLIAMS COMPANY, OF CLEVELAND, OHIO, A CORPORATION OF OHIO.

WHEEL-PAINTING MACHINE.

No. 834,250.

Specification of Letters Patent.

Patented Oct. 30, 1906.

Application filed May 11, 1906. Serial No. 316,265.

To all whom it may concern:

Be it known that we, JAMES C. BEARDSLEE and WILLIAM J. CRITCHLEY, citizens of the United States, and residents of Cleveland, 5 county of Cuyahoga, and State of Ohio, have invented a new and useful Improvement in Wheel-Painting Machines, of which the following is a specification, the principle of the invention being herein explained and the best 10 mode in which we have contemplated applying that principle, so as to distinguish it from other inventions.

Our invention pertains to improvements in devices for mechanically painting wheels and 15 similar articles. The general class of such devices to which our invention belongs is that one in which the paint is applied by dipping the article bodily into a paint-tank or like receptacle. After raising the object out 20 of such tank it has been found desirable to whirl it rapidly in first one then the opposite direction in order to spread the paint thoroughly over the object's surface, as well as to remove by the action of the centrifugal force 25 thus developed any surplus of paint, such as would otherwise remain and mar the coat.

The object of the present invention is to provide in connection with the tank and hood usually characterizing machines of this 30 kind suitable mechanism whereby wheels or other objects can be more quickly and economically handled, and satisfactory results therewith more uniformly assured than has been possible with machines at present on the market. Said invention is a modification 35 of the device described and claimed in a pending application of one of the present inventors for Letters Patent of the United States, filed April 23, 1906, Serial No. 313,225; and 40 it consists of means hereinafter fully described and particularly set forth in the claims.

The annexed drawings and the following description set forth in detail certain mechanism embodying the invention, such disclosed means constituting but one of the various mechanical forms in which the principle of the invention may be used.

In said annexed drawings, Figure 1 represents a front elevation of a wheel-painting machine embodying our invention. Fig. 2 represents a side elevation of the same, as

viewed from the right in Fig. 1; and Fig. 3 is a plan view of such machine.

The preferred form of paint-receptacle 55 (shown in the above figures) comprises a semicircular metallic tank A, the relatively narrow body portion of which is provided with a broad flaring top or rim a. The radius of the tank-body should be great enough 60 to permit the ready accommodation therein of the largest wheel upon which it is desired to operate, there being recesses or pockets a' in the flaring rim a of the tank adapted to receive the hub of the wheel when the latter is 65 lowered into the tank. It is designed that such tank be sunk into a recess in the floor in order to save space and render all parts of the machine proper more accessible. When thus sunk into the floor, the tank rests upon 70 a flange a², that encircles the same a short distance below rim a. This flange also serves as a convenient point for the attachment to the tank of handles a³, whereby the tank may be removed from its position in the 75 floor when desired. The purpose of this construction is to permit the ready changing from one kind of paint to another without having to use a different machine with each or going through a bothersome process of 80 emptying the tank of the one paint, cleansing the same, and then filling it with the other. Here it is merely necessary to exchange one tank for another, there being as many tanks as there are colors or kinds of 85 paint in regular use. The tanks, moreover, afford convenient receptacles for temporarily storing the paint when not being used, and covers may be provided therefor to lessen the loss from evaporation when they are standing idle. 90

We use in connection with the tank just described a removable hood of familiar form, and hence not illustrated. Such hood is preferably made of sheet metal and its width 95 is the same as that of the rim a, surmounting tank A, and its height is such as to readily accommodate a wheel when the latter is raised entirely above the level of the paint in tank A. Such hood is also usually made of 100 triangular cross-section, whereby it is adapted to facilitate the collection and return to the tank of the paint when thrown off by the rapid rotation of the wheel within the hood.

To support the wheel, both while being immersed in the paint-tank and while being rotated within the hood, we provide the following mechanism: Laterally of the tank, 5 or, rather, the recess in the floor in which such tank is placed when in use, and to one end of the same are securely mounted, on a suitable base C', two upright standards c. In bearings c' on standards c is journaled a horizontal- 10 tal drive-shaft C², the rear end of which projects some distance beyond the corresponding bearing and is provided with a driving-pulley C³. Intermediately of the two standards c there is pivotally mounted on such drive- 15 shaft C² a frame C, preferably consisting of an integral casting of general U shape. The point of pivotal support of frame C being near the base of the U the arms are caused to project alongside tank A, Figs. 1 and 3, and 20 their length is so proportioned as to bring their ends substantially in a plane passing through the center of such tank and superimposed hood B. In suitable bearings c², provided in the ends of these arms of frame C, 25 is journaled a spindle C⁴. Spindle C⁴ will obviously lie parallel with drive-shaft C², and its forward end projects out over tank A and within hood B when the latter is in position. Such forward end of the spindle is designed 30 to receive the wheel to be painted, the hub of the wheel being slipped directly onto the the same. To hold such wheel rotatively upon the spindle when the latter is being rotated, arms c³ are mounted near the spindle's 35 end and are bent forwardly to engage the wheel between its spokes. The outer end of each of these arms is spread in the manner clearly shown in Figs. 1 and 2, whereby any tendency of the wheel to slip off the spindle 40 pending such rotation is overcome.

From the description previously given of the manner in which frame C is oscillatorily mounted upon drive-shaft C² it will be evident that the former may be swung up and 45 down to raise and depress the spindle C⁴, mounted in its outer end, as desired. This swinging motion, of course, is entirely independent of any motion of rotation that may be given the shaft C² through driving-pulley 50 C³. Normally the frame is maintained in its raised position, illustrated in the several figures of the drawings, by a counterweight C⁵, adjustably secured on a bar C⁶, projecting outwardly from the frame's base. Such 55 counterweight is intended to be sufficiently heavy to maintain the frame in the position indicated even when a wheel is attached to spindle C⁴. To swing the frame to depress its outer end, so as to immerse such wheel in 60 tank A, a handle c⁶ is conveniently attached to counterweight C⁵. In order to steady frame C against undue vibration to which it might be liable when in its raised position, and particularly when spindle C⁴ is being rotated, a standard D, provided with a half-

bearing d, is positioned so as to permit the spindle to lie therein when the frame is tilted upwardly. This bearing-rest, in addition to steadyng the frame, serves also as a stop to prevent the same from swinging too far. 70 While only one such standard D is shown, this, when disposed so as to engage the spindle midway between its ends being considered sufficient, two or more rests may be provided, if desired. 75

To effect the reversible rotation of spindle C⁴ with attached wheel, such as has been described as being most efficacious in securing the even and thorough spreading of the paint, the spindle is operatively connected 80 by any suitable means with drive-shaft C². The approved form of connection here shown comprises a pair of pulleys C⁶ C⁷, rotatably mounted upon the drive-shaft and respectively connected to rotate in opposite directions two similar pulleys C⁸ and C⁹, rotatably mounted upon the spindle. Both sets of pulleys are obviously most conveniently mounted on that portion of their respective shafts inclosed between the arms of frame 85 C. A double-cone friction-clutch C¹⁰, splined on drive-shaft C² intermediately of pulleys C⁶ and C⁷ and shiftable into contact with either of said pulleys by a hand-lever c⁶, enables the operator to easily connect spindle 90 C⁴ with shaft C² to drive the former in whichever direction desired and at varying rates of speed up to the maximum speed of the shaft. Normally hand-lever c⁶ is held by springs c⁷ to retain friction-clutch C¹⁰ in a neutral position out of contact with either of pulleys C⁶ C⁷. 95

As to the manner in which our improved wheel-painting machine is operated but little need be said, such operation having been in large part indicated in connection with the foregoing description of the machine's construction. It will suffice, accordingly, to point out that normally the wheel-supporting spindle C⁴ is maintained in the elevated position shown in the figures, in which position a wheel may be attached thereto with the greatest facility. Ordinarily one operative would attend to thus affixing and removing the wheels, while another would swing the frame and manipulate hand-lever c⁶. A 105 wheel having been thus attached by the first operative the second thereupon grasps handle c⁶ to depress the frame, and thereby dip the wheel in the tank. While thus semi-immersed, the wheel is given several turns, either by hand or by a slight pressure on lever c⁶, it being of course understood that too rapid a rotation of the wheel when in this position would be disastrous. By simply releasing handle c⁶ the frame is allowed to 110 swing back to its normal position, and thereby raise the wheel, which is thereupon rapidly rotated in first one direction, then the other, by swinging hand-lever c⁶ to shift clutch C¹⁰ with greater pressure than in the instance 115 120 125 130 135

already noted into contact with first one, then the other, of pulleys C⁶ C⁷. Again, by simply releasing a lever, this time c⁶, spindle C⁴ is disconnected from the driving-shaft, and as soon as the wheel ceases to revolve it may be removed and another substituted therefor.

Our machine, it is hence seen, permits an increase in the rapidity and consequent economy with which wheels can be painted. At the same time, by virtue of the arrangement of the several parts, the labor of handling the wheels, involved in putting them on and removing them from the machine, is greatly reduced, while by the fewness and simplicity in construction of the parts themselves the initial cost, as well as the expense of repairs, is reduced to a minimum.

Having thus described our invention in detail, that which we particularly point out and distinctly claim is—

1. In a machine for painting wheels and the like, the combination of a paint-receptacle, a rotatable member oscillatory mounted to one side of said receptacle on an axis substantially parallel with its own, said member projecting over said receptacle and being adapted to receive the object to be painted, and means adapted to rotate said member irrespective of its position about such axis of oscillation.

2. In a machine for painting wheels and the like, the combination of a paint-receptacle, an oscillatory frame adjacent thereto, a member rotatably mounted in the free end of said frame on an axis substantially parallel with the latter's axis of oscillation, said member projecting laterally over said receptacle and being adapted to receive the object to be painted, and means adapted to rotate said member irrespective of the position of said frame.

3. In a machine for painting wheels and the like, the combination of a paint-receptacle, an oscillatory frame adjacent thereto, a member rotatably mounted in said frame on a substantially horizontal axis, said member projecting laterally over said receptacle and being adapted to receive the object to be painted, and means adapted to rotate said member irrespective of the position of said frame.

4. In a machine for painting wheels and the like, the combination of a paint-receptacle, a pivotally-mounted frame independent of said receptacle but located adjacent thereto, said frame being adapted to occupy various angular positions about its pivotal axis, a member rotatably mounted in the free end of said frame and projecting laterally over said receptacle, said member being adapted to receive and hold the object to be painted, and means adapted to rotate said member irrespective of the position of said frame.

5. In a machine for painting wheels and the like, the combination of a paint-receptacle, a frame adjacent thereto, said frame being pivotally mounted at one end and being adapted to occupy various angular positions about its pivotal axis, means normally retaining said frame in one of said positions, a member rotatably mounted in the free end of said frame and projecting over said paint-receptacle, said member being adapted to receive and hold the object to be painted, and means adapted to rotate said member irrespective of the position of said frame.

6. In a machine for painting wheels and the like, the combination of a paint-receptacle, an oscillatory frame adjacent thereto, a rotatable member wholly supported in the free end of said frame and projecting laterally over said receptacle, said member being adapted to receive and hold the object to be painted, a counterweight normally maintaining said frame in a raised position, means for depressing said frame, and means adapted to rotate said member irrespective of the position of said frame.

7. In a machine for painting wheels and the like, the combination of a paint-receptacle, a rotary driving member independent of said receptacle but located adjacent thereto, a frame oscillatory about an axis substantially in line with the axis of said driving member, a member rotatably mounted in the free end of said frame and projecting laterally over said receptacle, such member being adapted to receive and hold the object to be painted, and means operatively connecting said member with said driving member.

8. In a machine for painting wheels and the like, the combination of a paint-receptacle, a pivotally-mounted frame adjacent thereto, a drive-shaft substantially in line with the axis of said frame, a spindle mounted in the free end of said frame and having one end projecting over said receptacle, such end being adapted to receive and hold the object to be painted, and reversible operating means connecting said spindle with said drive-shaft.

9. In a machine for painting wheels and the like, the combination of a paint-receptacle, a horizontal drive-shaft disposed laterally thereof, a frame oscillatory mounted on said shaft, a spindle mounted in the free end of said frame and having one end projecting over said receptacle, such end being adapted to receive and hold the object to be painted, and reversible operating means connecting said spindle with said drive-shaft.

10. In a machine for painting wheels and the like, the combination of a paint-receptacle, a horizontal drive-shaft disposed laterally thereof, a frame pivotally mounted upon said shaft, a spindle mounted in the free end of said frame and having one end projecting over said receptacle, such end being adapted

to receive and hold the object to be painted, two pulleys rotatably mounted upon said shaft and connected to rotate said spindle in opposite directions, and means for respectively rotatively securing said pulleys to said shaft.

11. In a machine for painting wheels and the like, the combination of a paint-receptacle, a horizontal drive-shaft disposed laterally thereof, a frame pivotally mounted upon said shaft, a spindle mounted in the free end of said frame and having one end projecting over said receptacle, such end being adapted to receive and hold the object to be painted, 15 a counterweight normally maintaining said frame in a raised position, means for depressing said frame, two pulleys rotatably mounted upon said shaft and connected to rotate said spindle in opposite directions, and a 20 clutch adapted to rotatively secure said respective pulleys to said shaft, said clutch being normally maintained in a neutral position.
12. In a machine for painting wheels and the like, the combination of a paint-receptacle, a pivotally-mounted frame adjacent thereto, said frame being adapted to occupy various angular positions about its pivotal axis, a member rotatably mounted in the 25 free end of said frame and projecting over said receptacle, said member being adapted to receive and hold the object to be painted, 30 means adapted to rotate said member irre-

spective of the position of said frame, and a hood surmounting said paint-receptacle and 35 inclosing said member.

13. In a machine for painting wheels and the like, the combination of a paint-receptacle, an oscillatory frame adjacent thereto, said frame being adapted to occupy various 40 angular positions about its axis of oscillation, a shaft rotatably mounted in the free end of said frame and projecting over said receptacle, said shaft being adapted to receive and hold the object to be painted, and a fixed 45 support adapted to engage said shaft to steady the same in one position of said frame about its axis.

14. In a machine for painting wheels and the like, the combination of a paint-receptacle, a pivotally-mounted frame adjacent thereto, said frame being adapted to occupy various angular positions about its pivotal axis, a shaft rotatably mounted in the free 50 end of said frame and projecting over said receptacle, said shaft being adapted to receive and hold the object to be painted, and a standard provided with an open bearing disposed to engage said shaft to steady the same 55 when said frame occupies its upper position. 60

Signed by us this 7th day of May, 1906.
